UNITED STATES PATENT OFFICE

132,683

DESIGN FOR A TOOL DRIVER

Milton E. Foster, near Seattle, Wash.

Application March 24, 1942, Serial No. 106,304

Term of patent 14 years

To all whom it may concern:

Be it known that I, Milton E. Foster, a citizen of the United States, residing near Seattle, in the county of King and State of Washington, have invented a new, original, and ornamental Design for a Tool Driver, of which the following is a specification, reference being had to the accompanying drawing, forming part thereof.

Figure 1 is a side elevational view of a tool driver, showing my new design and Figure 2 also shows the tool driver in elevation, from a view point at 90° from that of Figure 1.

I claim:

The ornamental design for a tool driver, substantially as shown.

MILTON E. FOSTER.
